(No Model.)

G. W. KERN.

FIRE ESCAPE.

No. 322,613.

Patented July 21, 1885.

UNITED STATES PATENT OFFICE.

GEORGE W. KERN, OF CHILLICOTHE, OHIO.

FIRE-ESCAPE.

SPECIFICATION forming part of Letters Patent No. 322,613, dated July 21, 1885.

Application filed April 8, 1885. (No model.)

To all whom it may concern:

Be it known that I, GEORGE W. KERN, a citizen of the United States, residing at Chillicothe, in the county of Ross and State of Ohio, have invented certain new and useful Improvements in Fire-Escapes; and I do hereby declare that the following is a full, clear, and exact description of the invention, which will enable others skilled in the art to which it appertains to make and use the same.

Figure 1 is a perspective view of my improved fire-escape, showing the same in position for operation. Fig. 2 is a vertical sectional view of the same.

15 The same letters refer to the same parts in both the figures.

This invention relates to fire-escapes of that class which may be adjusted and operated by hand by the persons seeking to escape from 20 burning buildings; and it has for its object to provide a device of this class which shall possess superior advantages in point of simplicity, durability, and general efficiency.

With these ends in view, it consists in the 25 improved construction and arrangement of parts, which will be hereinafter fully described, and particularly pointed out in the claims.

In the drawings hereto annexed, A designates the frame of my improved fire-escape, 30 which consists of side pieces, B B, constructed of metal, and provided at their lower ends with inwardly-extending jaws C C, to which a bail or holder, D, is riveted or otherwise secured. The upper ends of the side pieces, 35 B B, are connected by a perforated cross-piece, E, of which further mention will hereinafter be made. The side pieces, B B, are provided near their lower ends with bearings for a transverse shaft, F, carrying a spool or 40 drum, G, on which is wound a wire rope, H, one end of which is attached to the said drum, and the other end of which passes through suitable eyes, I I, attached to the inner side or sides of one or both of the side pieces of 45 the frame and through the perforation J in the top piece, E, connecting the said side pieces. The upper or outer end of the said wire rope is provided with a loop, K, whereby it may be made fast to a window-sill or to 50 some other suitable fixed point.

Secured pivotally to each of the side pieces, B, of the frame is a brake-lever, L, one end of

which has a shoe, M, adapted to bear against one of the cheeks N of the drum G, and the other end of which forms a handle, N', which may be 55 readily reached by the operator.

A life belt, basket, or other suitable device is in practice to be attached to the bail or holder D at the lower end of the frame.

From the foregoing description, taken in 60 connection with the drawings hereto annexed, the operation and advantages of this invention will be readily understood. The construction is simple and inexpensive, and the entire apparatus occupies but little space. It 65 may thus be readily carried in a trunk or hand-bag, and may, when occasion requires, be readily made fast to a window-sill or other suitable place for the purpose of escaping from a burning building. It will be noticed 70 that the frame being constructed of metal, and the rope being a wire rope, the device is incombustible and fire-proof.

I would have it understood that in the manufacture of this device I do not limit myself to 75 the precise construction herein set forth, but reserve to myself the right to all modifications which may be resorted to without departing from the spirit of my invention.

Having thus described my invention, I claim 80 and desire to secure by Letters Patent of the United States—

1. In a fire-escape, the combination of a frame constructed of metallic side pieces connected at their upper and lower ends, a drum 85 mounted upon a shaft journaled between the lower ends of the said side pieces, and a wire rope coiled upon the said drum and passing over a pulley and through a series of eyes in the connecting-pieces of the sides of the frame, 90 substantially as and for the purpose herein set forth.

2. In a fire-escape, the combination of a pair of metallic side pieces, connected at their upper ends by a perforated cross-piece, and 95 at their lower ends by a bail or holder connecting the overlapping lower ends of the said side pieces with a drum journaled between the said side pieces, and a wire rope coiled upon the said drum, and having its end passed over 100 a pulley and through guide-eyes upon the inner sides of the frame-pieces and through the perforation in the upper cross-piece, substantially as and for the purpose set forth.

3. In a fire-escape, the combination of the herein-described metallic frame, the drum journaled between the sides of the same, the wire rope coiled upon the said drum and passing through a series of suitable guide-eyes, and a brake-lever pivoted to one of the sides of the frame, and having a shoe adapted to bear against the periphery of the drum, and

an operating-handle, substantially as herein described, for the purpose set forth. 10

In testimony whereof I affix my signature in presence of two witnesses.

GEORGE W. KERN.

Witnesses:

R. T. WORTHINGTON.

FERDINAND HUMMEL.
